UNITED STATES PATENT OFFICE.

CHARLES H. HISER, OF SPRINGFIELD, OHIO, ASSIGNOR TO THE SPRINGFIELD METALIC CASKET COMPANY, OF SPRINGFIELD, OHIO, A CORPORATION OF OHIO.

DESIGN FOR AN EAR FOR HANDLES FOR BURIAL CASES.

Application filed January 15, 1923. Serial No. 4,884. Term of patent 14 years.

To all whom it may concern:

Be it known that I, CHARLES H. HISER, a citizen of the United States, residing at Springfield, in the county of Clark and State of Ohio, have invented a new, original, and ornamental Design for Ears for Handles for Burial Cases, of which the following is a specification, reference being had to the drawing, forming part thereof.

Fig. 1 is a front elevation.

Fig. 2 is a vertical section.

I claim:

The ornamental design for ears for handles for burial cases as shown.

CHARLES H. HISER.
